FOOTWEAR

Application filed April 15, 1927. Serial No. 184,024.

Our invention relates to therapeutics, and more specifically to curing foot ailments including correction of a large number of various disabilities and weaknesses commonly referred to as fallen arches. Among the objects and advantages of the invention may be enumerated the extension of the range of service of a single device to function properly throughout the various stages of recovery.

In the drawings:

Figure 1 is a longitudinal section of a shoe last;

Figure 2 is a plan of the metal parts of a supporting arch;

Figure 3 is a longitudinal section through the partly assembled parts of the sole of a shoe; and

Figure 4 is a phantom diagram of a completed device in use.

The last 10 is provided with a special concavity 12 to assist in building up the completed shoe in the proper shape. Upon this last is laid the insole 14, which is pressed down to lie smoothly against the bottom of the concavity 12. The uppers 15 are lapped over the edge of the insole and the welt 16 is fastened to the insole and uppers in the usual way. Near the toe, a layer of filling 18 is positioned next the insole 15, which filling may be of a tarry or cementitious nature. Back of the filling is positioned a padding 20, such as loose hair felt or cork.

The arch comprises a shank member 22 and a front section or flap 24. They are articulated together by means of side tongues 26 on the shank member and a central tongue 28 on the flap, continued as an embossment across the body at 29 to strengthen and stiffen the structure. The central tongue 28 is offset from the plane of the body of the flap so as to lie on the opposite side of the shank member, the uppermost side when in use as in Fig. 4. This articulation permits the flap to pivot about a transverse hinge line at the rear edge of the body of the flap in a downward direction from the position of Figure 4, but not in an upward direction. When it is tipped down, a

slight tilt sidewise in either direction is also permitted.

In assembling the shank member with the parts already discussed in connection with Fig. 3, a strip of adhesive tape, such as a material commonly referred to as "bicycle tape," is wrapped once completely around the flap by laying one end of the strip over the tongue 28, as at 30 in Fig. 3, then back under the entire flap as at 32, and again over the flap as at 34, and back over almost the entire length of the reach, as at 36. This provides a fabric hinge connection at 38 in addition to the metallic interconnection formed by the tongues 26 and 28.

The shank member is provided with bosses 40 and the tongue 28 has a similar boss 42. In addition to stiffening the metal, these bosses embed themselves slightly in the padding 20. This, combined with the adhesion of the tape to the padding 20 and to the outer sole 44, functions in combination with fixed attachment means at the extreme rear end only, as at 46, to keep the arch support as a whole in place. The adhesion may be somewhat improved by laying short transverse strips of adhesive tape at 48 and at 50 to increase the area of adhesion.

The front end of the flap is bent back on itself as at 52, and then curved upward to form a dome 54 resiliently supported by the connection at 52. This makes this portion of the support seem soft and yielding.

Referring now to Fig. 4, it will be apparent that the dome 54 is substantially centrally located with respect to the metatarsal arch of the wearer. This is true both in a longitudinal and a transverse sense. It will also be noted that the thickness of the integument between the metatarsal bone 56 and the arch 54 is approximately equal at the front and rear ends of the arch.

When the device is in use, the placing of the heel 58 upon the ground affords the navicular bone 60, the first cuneiform bone 62, and the second and third cuneiform and cuboid bones (not shown) a considerable measure of support by cantilever action, for the reason that the posterior end of the shank member 22 extends back well under

the point of the calcaneous bone 64, which affords a purchase far enough back from the front edge of the keel to permit such action. During such action and before the load is imposed on the forward part of the foot, the flap 24 may pivot freely downward, i. e., there is no artificial support in front of the tarsometatarsal articulations.

The transfer of a small amount of weight toward the front part of the foot will bring the toe 52 into supporting relation with the ground, after which both the tarsus and metatarsus are supported by beam action. The fulcrum at 52 is preferably back of the metatarsal-phalangeal articulations, but the force transmitted to the foot by the arch structure is primarily from the dome 54, which is still further back under the center of the metatarsal arch.

20 Since the only fixed attachment for the metal arch is at the extreme rear, slight lateral shifting of the front end can occur. This permits the front end to adjust itself laterally to a perfect fit.

25 Without further elaboration, the foregoing will so fully explain the gist of our invention, that others may, by applying current knowledge, readily adapt the same for use under various conditions of service, without 30 eliminating certain features which may properly be said to constitute the essential items of novelty involved, which items are intended to be defined and secured to us by the following claims.

35 What is claimed is:

1. The method of assembling a shoe containing a two-piece arch support with interlocking projections forming a one-way flexible connection between the pieces; which 40 comprises wrapping adhesive tape around one piece with one end of said tape passing through the connection and the other end laid across said first end and over said other piece; laying the unit thus assembled on the 45 inner sole; and securing it only at the rear end near the rear end of the heel of the shoe.

2. The method of assembling a shoe containing a two-piece arch support with interlocking projections forming a one-way flexible connection between the pieces; which 50 comprises wrapping adhesive tape around one piece with one end of said tape passing through the connection and the other end laid across said first end and over said other 55 piece; laying the unit thus assembled on the inner sole; and securing it in place.

3. The method of supporting arches which 60 comprises furnishing the navicular, cuboid, and all the cuneiform bones with partial support by cantilever action from the heel structure of a shoe leaving the foot free to flex downwardly in the metatarsal region; shaping an upwardly convex dome in the insole conforming to and coextensive both transversely and longitudinally with the con-

cavity of the metatarsal arch; supporting the center of said dome resiliently; and replacing the cantilever tarsal support by beam support when the removal of weight from the heel makes it incapable of furnishing cantilever support.

4. A shoe comprising an insole; an outer sole; a filling between said soles back to the metatarsophalangeal articulations; a padding between said soles back of said filling; a reinforcing means between said soles running back from said filling to a point near the rear end of the heel, and embedded in said padding; said reinforcing means having an intermediate hinge connection permitting the middle to flex up but not down from normal position; projections on said means, and adhesive tape for holding said means in place; and a positive attachment for the extreme rear end of said means.

5. A shoe comprising an insole; an outer sole; a filling between said soles back to the metatarsophalangeal articulations; a padding between said soles back of said filling; a reinforcing means between said soles running back from said filling to a point near the rear end of the heel, and embedded in said padding; said reinforcing means having an intermediate hinge connection permitting the middle to flex up but not down from normal position; and projections on said means, and adhesive tape for holding said means in place.

6. A shoe comprising an insole; an outer sole; a filling between said soles back to the metatarsophalangeal articulations; a padding between said soles back of said filling; a reinforcing means between said soles running back from said filling to a point near the rear end of the heel, and embedded in said padding; said reinforcing means having an intermediate hinge connection permitting the middle to flex up but not down from normal position; and projections on said means for holding said means in place.

7. A reinforcing arch for shoes comprising a shank member extending inside the sole from near the rear end of the heel to approximately the tarsometatarsal articulations; a leaf hingedly connected to the front end of said shank member, and extending forward to form a fulcrum slightly behind the metatarsophalangeal articulations; and a dome resiliently mounted above said leaf at about the longitudinal and transverse center of the metatarsal arch; the hinge connection permitting said leaf to swing down but not up with respect to said shank member.

8. A reinforcing arch for shoes comprising a shank member extending inside the sole from near the rear end of the heel to approximately the tarsometatarsal articulations; a leaf at the front end of said shank member extending forward to form a ful-

crum slightly behind the metatarso-phalangeal articulations; and a dome resiliently mounted above said leaf at about the longitudinal and transverse center of the meta-
5 tarsal arch.

9. A shoe comprising in combination, a multiply sole, an arch support between the plies, padding between said support and the ply above it, and reinforcing bosses on said 10 support embedded in said padding to hold the support in place, said support being fixedly fastened in place near its extreme rear end only.

10. A shoe comprising in combination a 15 multi-ply sole structure, a hingedly connected metal arch support between said plies, and flexible fabric adhering to the sections of said support adjacent the hinge to hold said sections against separation and to 20 reduce noise created by the movement of the sections of said support.

11. A shoe comprising in combination an insole, an outer sole, an arch support between said soles running back to a point 25 near the rear end of the heel, plastic padding between said soles and distributed around said support to embed the latter, yielding means for connecting said support to said shoe only at the rear end of said 30 support to permit said support to move slightly transversely of said shoe so as to adjust itself to the arch of the wearer, and projections on said support embedded in 35 said padding to resist shifting of said support, but permitting movement thereof to secure the aforesaid adjustment.

12. A shoe comprising in combination an insole, an outsole, a metal arch support built into said shoe and lying between said insole 40 and outsole, said support consisting of a forward part having a dome-like transverse metatarsal arch support lying under the anterior metatarsal arch and behind the heads 45 of the metatarsal bones, a rear part and a hinged connection between said forward and rear parts and being constructed and arranged to permit said parts to flex upwardly and to separate longitudinally, and means associated with said connection for limiting 50 the downward flexure of said arch.

13. A shoe comprising in combination an insole, an outsole, a metal arch support built into said shoe and lying between said insole and outsole, said support consisting of a 55 forward part having a dome-like member providing a transverse metatarsal arch support lying under the anterior metatarsal arch and behind the heads of the metatarsal bones, a rear part, said parts having inter-
60 fitting fingers at their adjacent ends which permit the arch to flex upwardly and said parts to separate, and means associated with said fingers for limiting downward flexure of said arch.

65 14. A shoe comprising in combination an

insole, an outsole, a metal arch support built into said shoe and lying between said insole and outsole, said support consisting of a forward part having a convex transverse metatarsal arch support lying under the anterior metatarsal arch and behind the heads of the metatarsal bones and generally conforming to the contour of the normal transverse arch, a rear part extending toward the heel and adapted to receive the weight of the heel, said parts being provided with inter-engaging means which permit upward flexure of the arch and longitudinal separation of said parts, said rear part being a portion which extends under the forward portion 70 and is adapted to exert an upward pry thereon to produce a lifting action on the metatarsal arch when weight is placed on the heel, and means for preventing downward flexure of said arch beyond a given 75 point.

15. A shoe comprising in combination an insole, an outsole, an arch support comprising a plurality of separable relatively flexible sections, and adhesive tape wrapped about said sections in the region of their juncture to prevent separation thereof in assembly of the shoe and to eliminate noises in the flexing of said sections.

16. In a shoe the combination comprising a metal arch support having a forward part provided with a convex metatarsal arch support lying under the anterior metatarsal arch and behind the heads of the metatarsal bones, a metal rear portion extending toward the heel of the shoe, a hinged connection between said forward and rear parts and constructed and arranged to permit said parts to flex upwardly, and limiting means associated with said hinged connections to limit the downward flexure of said parts so as to provide a support for the longitudinal arch.

17. In a shoe the combination comprising a metal shank whose front end is bent back upon itself to overlie the forward portion of said shank to provide a convex metatarsal arch support lying under the anterior metatarsal arch and behind the heads of the metatarsal bones, a metal rear portion extending toward the heel of the shoe, a hinged connection between said forward and rear parts and constructed and arranged to permit said parts to flex upwardly, and limiting means associated with said hinged connection to limit the downward flexure of said parts so as to provide a support for the longitudinal arch.

In testimony whereof, we have signed our names to this specification.

WILL N. SECHLER.
SAMUEL GOODMAN.
